UNITED STATES PATENT OFFICE.

FRANK E. WALTERS, OF TOLEDO, OHIO.

STAIRWAY-BLOCK AND STAIRWAYS MADE THEREFROM.

1,370,718.

Specification of Letters Patent.

Patented Mar. 8, 1921.

Application filed October 16, 1919. Serial No. 330,973.

To all whom it may concern:

Be it known that I, FRANK E. WALTERS, a citizen of the United States, and a resident of Toledo, in the county of Lucas and 5 State of Ohio, have invented a certain new and useful Stairway-Block and Stairways Made Therefrom; and I do hereby declare the following to be a full, clear, and exact 10 description of the invention, such as will enable others skilled in the art to which it appertains to make and use the same, reference being had to the accompanying drawings, and to the characters of reference marked thereon, which form a part of this 15 specification.

My invention has for its object to provide a stairway block or step formed of hardened reinforced plastic material such as cement. Blocks or steps made in accordance with my 20 invention are so formed that they may be made individually, that is, apart from the formation of the stairway, and then may be assembled to form a stairway. This provides a great advantage in the construction 25 of stairways, inasmuch as any number of blocks may be made in a mold and then assembled to form the stairway where ordinarily it requires the formation of a supporting structure for the plastic material 30 while it is hardening and in positions that are often difficult to construct. Moreover, shrinkage of monolithic stairways often produces cracks and consequently weakness of the stairway when finally constructed. 35 By my invention is provided a block or step that is so constructed and reinforced that a number of steps may be abutted at opposite edges and thus form a light weight though strong and durable stairway.

40 Furthermore my invention provides a stairway formed of a plurality of blocks that are so reinforced and supported that the blocks may be easily assembled to form a strong and efficient stairway.

45 The invention may be contained in stairways of different forms. For purposes of illustration I have selected a construction containing the invention and shall describe it hereinafter, it being understood that the 50 details may be varied by those skilled in the art and structures so formed may still contain the invention. The structure selected is illustrated in the accompanying drawings.

55 Figure 1 of the drawings illustrates a

broken perspective view of part of the stairway containing my invention. Fig. 2 is a vertical sectional view taken on the line 2—2 indicated in Fig. 3. Fig. 3 illustrates a side view of a portion of the stairway, one 60 of the supporting channel iron shown in Fig. 1 having been removed.

In the drawings 1 are blocks that form steps of the stairway. The blocks are formed of hardened plastic material such as 65 suitable cement composition commonly used in concrete work. Each block 1 is provided with a riser portion 2 and a tread portion 3. The riser and tread portions of each block are connected together integrally with a 70 plurality of webs 4 that are disposed in parallel relation and at suitable distances apart along the step, that is, across the width of the stairway. When assembled the webs of the blocks are placed in line so as to carry 75 the strain through the webs from the topmost step to the bottommost step and the lower floor from which the stairway rises.

The upper and lower edges of each block or step are provided with rods 5 and 6 that 80 extend across the stairway, that is, the length of the step. The rods 5 and 6 are connected together by a plurality of rods 7 that extend through the webs 4. A rod 8 is located near the corner formed by the riser 85 and the tread portions of the stairway, and a reinforcing mesh 9 extends from the rod 8 to the rod 6 through the tread portion and from the rod 8 to the rod 5 through the riser portion. Thus each step is reinforced 90 to withstand the strains to which it would be subjected when supported in the manner provided by my invention as hereinafter described.

A pair of channel irons 10 having flanges 95 11 extending toward each other form main supporting means of the stairway. The ends of the blocks or steps 1 may be inserted between the ends of the channel irons and between the flanges of the channel irons and 100 then slid into position. Preferably the blocks are inserted between the upper ends of the channel irons and slid down until they come in contact with the next lower step or the lower floor from which the stairway rises. The ends of the blocks thus rest on the lower flanges 11 of the channel irons 10 and the blocks abut along the upper and lower edges, that is, the rear edges of the 105 tread portions and the lower edges of the 110

riser portions of the steps. The lower edge of the riser portion and the rear edge of the tread portion of each block are provided with inclined surfaces 12 and 13 that fit the inclined surfaces of the lower flanges 11 of the channel irons 10. The corner 14 of the step fits into the channel irons, particularly, the lower surfaces of the upper flanges of the channel irons, when the step 10 is in position between the channel irons and thus the steps are securely held from buckling in the channel irons. The web portions 4 may also be made so that their lower edges are located above the plane of the upper surfaces 15 of the lower flanges 11 to give sufficient clearance of the end webs of each step. Moreover the upper end lower edges of each step have abutting or beveled surfaces 16 that are located at right angles to the surfaces of the lower flanges of the channel irons and consequently are inclined with respect to the riser and tread portions of the steps. The step is thus provided with abutting and supporting edge surfaces which, in conjunction 20 with channel irons, securely interlock and support the steps and form an exceedingly strong and durable stairway.

If desired the tread portions 3 may be provided with recesses that extend substantially the length of the steps and near the corner thereof and in which may be located metallic strips such as lead strips 15 that prevent slipping to a material extent when the stairway is in use. The web 4 at each 30 end of the step is cast with a hole so that it may be bolted to channels 10, or each web 4 may be cast with a hole so that a long bolt 17 may be passed through these webs and channels and bolted on either end.

40 I claim:—

1. In a block or step for stairways formed of hardened plastic material, having riser and tread portions, the riser and tread portions having beveled outer surfaces and web 45 portions interconnecting integrally the under and rear sides of the tread and riser portions respectively, reinforcing rods extending lengthwise through the step and web portions and rods extending transverse 50 and through the step and web portions and secured at their ends to the first named rods.

2. In a stairway, a plurality of blocks or

steps formed of hardened plastic material, each of the blocks having a riser and tread portions, the riser and tread portions having beveled outer surfaces located at opposite corners of the block and adapted to abut the corresponding surfaces of the blocks placed in juxtaposition therewith in the stairway, each of the blocks having web portions interconnecting integrally the under and rear sides of the tread and riser portions respectively and located in alinement with the web portions of the blocks placed in juxtaposition therewith, and reinforcing rods extending lengthwise and through the step and web portions.

3. In a stairway, a plurality of blocks formed of hardened plastic material, the blocks having riser and tread portions, a 70 pair of parallel inclined channel irons having their flanges extending toward each other and located at opposite ends of the blocks, the flanges extending over and underneath the ends of the blocks for securing the blocks in position.

4. In a stairway, a pair of parallel inclined channel irons having their flanges extending toward each other, a plurality of steps formed of blocks, the blocks having beveled abutting surfaces at the rear and upper corners of the blocks and at the lower and forward corners of the blocks, the ends of the blocks located in the channels of the channel irons.

5. In a stairway, a pair of parallel inclined channel irons having their flanges extending toward each other, a plurality of steps formed of blocks of hardened plastic material having riser and tread portions, the riser and tread portions having beveled outer surfaces located at the rear and upper corners of the blocks and at the front and lower corners of the blocks forming abutting surfaces between adjoining blocks, the 95 ends of the blocks fitting between the flanges of the channel irons, the blocks having web portions formed integrally with the tread portions and the riser portions of the blocks and located in alinement with the web portions of the adjoining blocks.

In testimony whereof I have hereunto signed my name to this specification.

FRANK E. WALTERS.
